SWITCH CONTACT STRUCTURE

Filed Feb. 28, 1930

Inventor:
William K. Rankin,
By Charles E. Muller
His Attorney.

UNITED STATES PATENT OFFICE

WILLIAM K. RANKIN, OF LANSDOWNE, PENNSYLVANIA, ASSIGNOR TO GENERAL ELECTRIC COMPANY, A CORPORATION OF NEW YORK

SWITCH-CONTACT STRUCTURE

Application filed February 28, 1930. Serial No. 432,245.

My invention relates to switch contact structure, and more particularly to contact structure for large capacity circuit breakers of the fluid-break type.

When switches of the fluid-break type, as oil circuit breakers, are used to interrupt large power currents, the contacting surfaces of the switch and associated parts may be severely burned by the effects of arcing so that good conducting engagement is not obtained unless the switch parts are frequently replaced. In the usual contact rod and segment arrangement, the arc is drawn between the end of the contact rod and the adjacent portions of the segments upon opening of the breaker, with the result that the segments are often burned and coated with an oxide film in parts so that the contact rod is unable to make a clean conducting engagement there-with upon subsequent closure of the switch.

It is a principal object of my invention to provide an improved switch contact structure, particularly useful for switches of the fluid-break type, which shall be simple and rugged in construction and efficient in operation, and which shall localize the effects of burning so as to obtain clean conducting engagement between the switch parts.

My invention will be more fully set forth in the following description referring to the accompanying drawing, and the features of novelty which characterize my invention will be pointed out with particularity in the claims annexed to and forming a part of this specification.

Referring to the drawing, the single figure thereof is an elevational cross-sectional view of a portion of a circuit breaker embodying my invention.

By way of example, but without limitation thereto, my invention is illustrated as embodied in an oil circuit breaker of the explosion chamber type comprising a lead-in conductor 1 electrically connected to the usual adapter structure 2 which supports the explosion chamber and associated contact structure. The explosion chamber, which is mounted upon the depending portion 3 of the adapter, comprises a cover member 4 secured in any suitable manner to the portion

3 and a cylindrical steel casing 5 forming the main part of the chamber clamped to and supported by the cover member 4 for enclosing the stationary contact structure. The cylindrical member 5 is provided with an opening at its lower end within which is mounted an insulating throat bushing 6 having an outwardly flared opening 7 through which the movable contact rod 8 may move to make and break the circuit within the chamber. The lower portion of the explosion chamber is provided with insulating and reinforcing structure, including a plate 9 upon which the outer cylindrical insulating shield 10 is mounted. An insulating lining 11, cylindrical in form, is likewise disposed within the explosion chamber. The exact details of construction of the explosion chamber form no part of my present invention, which may be incorporated in an explosion chamber of any well known construction.

Mounted within the explosion chamber is the coacting contact structure for the contact rod 8 comprising supporting and contact retaining means including a member 12 having an annular flange 13 for securing the same, as by the bolts 14, to the cover member 4 of the chamber. The member 12 comprises a cylindrical portion 15, which extends through the cover plate 4, having an annular limiting shoulder 16 and a reduced portion 17 within which a contact member 18 is guided for reciprocal movement. The contact member 18 which may be cylindrical in form as illustrated, is provided with a guide rod 19 adapted to extend through an aperture 20 in the end portion 21 of the cylindrical part 15, and is biased by resilient means, as the spring 22, towards a limiting position wherein the flange 23 of the contact member engages the limiting shoulder 16.

For the purpose of supporting conducting means adapted to engage the contact member, the contact retaining means likewise includes a shell-like member 24 which is suitably secured, as by threaded engagement at 25, to the member 12, and is provided at its lower end with an opening 26 through which the lower part of the contact member may

- extend or protrude when in its limiting position. Mounted within the member 24 and disposed circumferentially of the contact member, are conducting means, as the contact segments 27, resiliently biased by springs 28 into conducting engagement with the contact member. The conducting segments are electrically connected, as by the conducting strips 29 to the member 12, which is in turn in electrical contact with the adapter 2.
- In the position illustrated in the drawing, the breaker is in the open circuit position wherein the contact member 18 is biased by the spring 22 into its lower limiting position and into sliding engagement with the conducting segments 27. The movable contact rod 8, upon closure of the breaker, moves upwardly into the explosion chamber 20 through the flared opening in the throat bushing 6 and abuts the surface 18' of the contact member so that initial contact is thereby established. The spring 22 is so adjusted that it is under initial tension, thereby insuring firm contact pressure between the abutting surfaces at the moment of contact so as to minimize the effects of burning due to insufficient contact pressure. Upon further closing movement of the contact rod, the member 18 is forced upwardly against the tension of spring 22 so that the contact rod 8, which moves within the retaining portion 24, is now in conducting engagement with the segments 27. In the fully closed position of the switch, the abutting surfaces of the rod 8 and member 18 are disposed above the segments 27 so that the segments engage the sides of the contact rod in the normal current carrying position of the switch.
- Upon opening the switch, the contact rod 8 starts to descend, and acceleration thereof during the opening movement is aided by the compressed spring 22. As the rod descends the contact member 18 remains in following abutting engagement with the rod, so that the conducting engagement between the segments is transferred from the rod to the contact member. Due to the fact that the movement of the contact member is not checked until the abutting end thereof has passed beyond the conducting segments and beyond the member 24, it will be apparent that the final arcing must take place between the said abutting surface 18' and the end of the contact rod 8. Accordingly, the effects of the arc are confined to contact surfaces which are not utilized during normal operation of the switch.
- Since the sides of the contact rod 8 remain comparatively free of the effects of arcing, and since the conducting segments 27 are protected from the effects of arcing by the contact member 18, it will be apparent that the switch parts during closure thereof are in clean conducting engagement with each other, thereby minimizing the effects of heat-

ing due to high resistance contact engagement. As the effects of arcing on the contact member 18 are localized at the abutting surface 18', the sides of the contact member which are in sliding engagement with the conducting segments 27 are likewise maintained clean and free of burning.

It shall be understood that my invention is not limited to the specific details of construction and arrangement thereof herein illustrated, and that changes or modifications may occur to one skilled in the art without departing from the spirit of my invention.

What I claim as new and desire to secure by Letters Patent of the United States is:

1. Switch contact structure for large capacity circuit breakers comprising a contact member mounted for reciprocal movement, conducting contact segments disposed circumferentially around said member and adapted to be resiliently biased into engagement therewith, and a movable contact rod adapted initially to abut one end of the contact member and thereafter move into engagement with said contact segments, the initial and final contact engagement upon closure and opening of the circuit breaker being at said abutting surfaces.

2. Contact structure for large capacity switches of the fluid-break type comprising a stationary contact retainer, a contact member guided therein for vertical movement, conducting segments mounted within said retainer circumferentially of said member and adapted to be resiliently biased into engagement therewith, resilient means for urging the contact member into position to be engaged by said conducting segments, and a movable contact rod adapted during closure of the switch initially to abut one end of the contact member and thereafter to be moved against the bias of said resilient means into conducting engagement with said segments.

3. Contact structure for large capacity switches of the fluid-break type comprising a stationary contact retainer, a contact member slidably mounted within said retainer, a spring for resiliently biasing said member towards a limiting position, conducting segments mounted within said retainer circumferentially of the contact member and resiliently biased into conducting engagement with said member when it is in its limiting position, and a movable contact rod adapted initially to abut said contact member during closure of the switch whereby the contact rod upon further movement overcomes the bias of said spring and moves into said retainer into conducting engagement with said segments, said spring being adapted to aid acceleration of the contact rod upon opening movement thereof.

4. Contact structure for large capacity switches of the fluid-break type comprising

- a stationary contact retainer, a contact member guided therein for reciprocal movement, a spring for urging said contact member into a limiting position, conducting means for electrically connecting the contact member to the contact retainer, and a movable contact rod adapted initially to abut one end of the contact member upon closure of the switch and to engage within the contact retainer said conducting means when the switch is in its fully closed position, said spring being under initial tension whereby the initial contact engagement at said abutting surfaces is effective to prevent burning of the contacts.
5. In an oil circuit breaker comprising an explosion chamber and a movable contact rod adapted to make and break the circuit within said chamber, coacting contact structure mounted within said explosion chamber for the movable contact rod comprising a contact retainer of conducting material, a contact member guided for reciprocal movement therein, and a spring for urging said contact member into a limiting position whereby a portion thereof extends beyond the contact retainer, said movable contact rod adapted to abut said extending portion of the contact member so that arcing during opening of the breaker is substantially confined to said abutting surfaces.
6. In an oil circuit breaker comprising an explosion chamber and a movable contact rod adapted to make and break the circuit within said chamber, coacting contact structure mounted within the explosion chamber for the movable contact rod comprising a stationary contact retainer, a contact member mounted therein for reciprocal movement, conducting means within said retainer adapted to be in conducting engagement with the contact member, and a spring for urging said contact member into a limiting position whereby it is in engagement with the conducting means, said movable contact rod adapted during closing movement of the switch initially to abut one end of the contact member and to move the same against the bias of said spring so that the contact rod engages the conducting means in the fully closed position of the breaker.
7. In an oil circuit breaker comprising an explosion chamber and a movable contact rod adapted to make and break the circuit within said chamber, coacting contact structure mounted within the explosion chamber comprising a movable contact member, conducting means adapted to be in sliding engagement with said member for carrying the current traversing said breaker, and a spring for urging said member into a current carrying position, said movable contact rod adapted to abut said member in its current carrying position upon making and breaking of the circuit whereby arcing is substantially confined to said abutting surfaces, the contact member adapted to be displaced against the bias of said spring by the contact rod when it is in its closed circuit position whereby the conducting means and contact rod are in full current carrying engagement.
8. In an oil circuit breaker comprising an explosion chamber and a movable contact rod arranged to make and break the circuit within said chamber, coacting butt contact structure mounted within said explosion chamber comprising a contact retainer of conducting material, a cylindrical contact member guided for reciprocal movement therein, and a spring for urging said contact member into following engagement with said contact rod and towards a limiting position with respect to said contact retainer, said movable contact rod adapted to abut the coacting surface of said contact member during the switch closing movement and to move said contact member against the bias of said spring so that contact is initially made and finally broken at said butt contact surfaces.
- In witness whereof I have hereunto set my hand this 25th day of February, 1930.
- WILLIAM K. RANKIN.
